UNITED STATES PATENT OFFICE.

OSCAR A. NORMAN, OF NEWARK, NEW JERSEY.

EMERGENCY MEANS OF EGRESS FROM ELEVATOR CARS.

Application filed August 15, 1923, Serial No. 657,517. Renewed October 24, 1924.

To all whom it may concern:

Be it known that I, OSCAR A. NORMAN, a citizen of the United States, and a resident of Newark, in the county of Essex and 5 State of New Jersey, have invented certain new and useful Improvements in Emergency Means of Egress from Elevator Cars, of which the following is a specification.

My invention relates to emergency means 10 of egress from elevator cars, and has for its object the provision of means of access to the emergency panel in the top or ceiling of an elevator car, which will be readily accessible when needed but will collapse 15 or fold into a small part of the elevator car and be out of sight except when used. My device is arranged to take up the least possible space in an elevator car and when collapsed is completely enclosed, and is thus 20 kept free from dirt or drippings of oil from the machinery and will be clean when its use is required.

In the specification and drawings I have 25 described and shown my device as a means of access to the emergency exit near the top or ceiling of an elevator car, as consisting of a series of folding steps. The use of foldable steps such as described is preferable to the use of the ordinary rung 30 ladder, but my invention is not limited to the use of such steps only.

In this specification I describe my device in its preferred form, but I do not intend to limit myself to such form, the scope 35 of my invention being pointed out and set forth in the claims.

Referring to the drawings,

Fig. 1 is a side elevation, partly in cross section, of the interior of an elevator car 40 showing my improved means of access to the emergency panel in the top of the car, as extended.

Fig. 2 is a front elevation of the interior of the same car.

Fig. 3 is a horizontal cross section of 45 Fig. 2, showing the steps folded up in the closet provided between the movable panel of my device and the exterior wall of the car.

An ordinary elevator car 1 is provided

with the usual exterior walls 2 and with the usual interior panels. In the top or ceiling of the car there is provided an emergency panel 20. This panel can be removed and provides a means of emergency exit or 55 egress from the car in case of trouble. The use of such an emergency exit is old and is not part of my invention, my invention residing in improved means of access to this emergency exit which I have provided. 60

In place of one of the interior panels of the elevator car I have a removable side panel 3 which has affixed to its interior side a series of foldable steps 4 fastened to it by means of attachment piece 5. The individual foldable steps 4 are pinned to piece 5 and rotate upon it. The steps 4 are fastened together at their exterior ends by hand-rail 6. The governing rod or hand-rail 6 is attached to the steps in 70 the same fashion and collapses when the steps are folded against the side panel. Folding arms 7 and 7', foldable at the joint 8, 8', are fastened to the exterior wall of the car at 9, 9', and to the removable side panel at 10 and 10' by means of attachment pieces. By means of these foldable arms the side panel can either be collapsed against the interior of the car, as shown in Fig. 3, or extended as shown in Fig. 1. The 80 panel when collapsed as in Fig. 3 rests upon flanges, such as 11, and leaves a closet between it and the exterior wall of the car. This closet is from 1 to 1 1/8 inches in depth and is adapted to hold the folded 85 steps with their attachments. The upper folding arm 7 is longer than the lower folding arm 7', and the panel when extended by means of these folding arms assumes a sloping position, as shown in Fig. 1. This 90 renders the steps easier to ascend. The steps, as previously described, are foldably attached to the side panel at 10, and are fastened together at their exterior ends by means of hand-rail 6, collapsible with said 95 steps and governing their folding. From the panel, near the place of attachment of the folding arm 7 at 12 but slightly offset therefrom, extends a small arm 13. This arm is rotatably attached to the panel at 100

12 and to the step at 15. It is also provided with a slot and the folding arm 7 is attached to this arm by means of pin 14 passing through a hole in the folding arm and through the slot in the arm 13 and movable in that slot. The same construction is provided for the smaller folding arm 7'. The steps 4; the governing rod or hand-rail 6, and the side arms 13 and 13', all fold when the folding arms 7 and 7' are collapsed and the panel returned to its closed position, the pin 14 sliding in the slot in the arm 13. The offset attachment of the arms 13 and 13' to the panel at 12 and 12', as shown, permits this folding and collapsing, but when the folding arms are extended and the panel placed in its sloping position, this offset causes the steps themselves to assume a substantially horizontal position despite the sloping position of the panel.

As will be seen from the foregoing description, I have provided a collapsible means of access to the emergency exit near the top or ceiling of the elevator car. When not used the whole device is contained in the small 1 inch or $1\frac{1}{8}$ inch closet between the removable side panel and the walls of the car. The panel can be locked if desired. When unlocked and extended the means of access provide a sloping series of steps which afford easy access to the emergency exit. In the preferred construction the steps may be solid and need not be the mere rungs of a ladder, although the ladder could be used if desired. The steps, despite the general sloping position of the panel, are substantially horizontal. They are likewise provided with a solid back portion which affords needed privacy to the person making the exit. The simple construction provided causes the steps to automatically open and close as the panel is drawn out or replaced and at the same time the steps open and fold respectively, and assume the horizontal position. The governing rod 6 which strengthens and holds the steps in place, likewise can function as a hand-rail to the person making the ascent. The placing of the steps or ladder between an exterior wall and the removable panel protects these parts from the oil and dirt so often found in elevator shafts. When the emergency means of egress is used the person ascending the steps moves directly toward the opening 20 so that it is comparatively easy to step out of the top of the elevator, furthermore the operator of the car is in an advantageous position with respect to the cover for the opening in the top of the elevator, so that the cover can be removed without the necessity of the operator working behind his back as would be necessary for example if he were forced to climb up the side of the elevator. The de-

vice is a practical, simple and efficient attachment for an elevator and is such that it does not impair the appearance of the car.

This panel can be a part of any one of the four sides of the elevator car, and by the use of the words "side panel" in the specification and in the claims I of course mean any one of the four sides of the car.

What I claim is:

1. In an elevator car, emergency means of egress near the top or ceiling of said car, and means of access to said egress means comprising foldable steps fixed to said car. 75

2. In an elevator car, emergency means of egress near the top or ceiling of said car, and means of access to said egress means comprising foldable steps fixed to a removable side panel of said car. 80

3. In an elevator car, an emergency means of egress near the top or ceiling of said car, and means of access to said egress means comprising foldable steps fixed to a removable side panel of said car and adapted to fold into a closet formed between said removable side panel and the exterior side wall of said car. 85

4. In an elevator car, an emergency means of egress near the top or ceiling of said car, and means of access to said egress means comprising foldable steps having as a back support a removable side panel of said car. 90

5. In an elevator car, an emergency means of egress near the top or ceiling of said car and means of access to said egress means, comprising a removable side panel, a series of foldable steps attached thereto adapted to fold into a closet formed between said side panel and the exterior side wall of said car. 95

6. A means of access to an emergency exit near the top or ceiling of an elevator car, comprising a removable side panel having a series of foldable steps attached thereto, means collapsibly holding said access means with respect to said car and means adapted to fold said steps when said access means are collapsed and to hold said steps substantially horizontal when said access means are extended. 105

7. A means of access to an emergency exit near the top or ceiling of an elevator car, a removable side panel, collapsible means attaching said panel to the side of said car, steps attached to said panel adapted to be folded or extended by the folding or extending of said collapsible means. 115

8. A means of access to an emergency exit near the top or ceiling of an elevator car, a removable side panel, collapsible means attaching said panel to the side of said car, steps attached to said panel adapted to be folded or extended by the folding or extending of said collapsible means, said steps adapted to fold into a closet formed between 120 125

said side panel and the exterior wall of said elevator.

9. A means of access to an emergency exit near the top or ceiling of an elevator car, a removable side panel, collapsible means attaching said panel to the side of said car, steps attached to said panel adapted to be folded or extended by the folding or extending of said collapsible means, said collapsible means adapted to permit said panel to extend into a sloping position and said foldable steps to assume at the same time a substantially horizontal position.

10. A means of access to an emergency exit near the top or ceiling of an elevator car, comprising a removable side panel, folding arms adapted to hold said access means collapsed or extended, a series of foldable steps attached to said side panel and adapted to be folded or extended by the folding or extension of said folding arms.

11. A means of access to an emergency exit near the top or ceiling of an elevator car, comprising a removable side panel, folding arms adapted to hold said access means collapsed or extended, a series of foldable steps attached to said side panel and means adapted to cause said steps to fold when said folding arms are collapsed and to assume a substantially horizontal position when said folding arms are extended.

12. A means of access to an emergency exit near the top or ceiling of an elevator car, comprising a removable side panel, folding arms adapted to hold said access means collapsed or extended, a series of foldable steps attached to said side panel and a rod governing the folding of said steps and adapted to cause said steps to fold when said folding arms are collapsed and to assume a substantially horizontal position when said folding arms are extended.

13. A means of access to an emergency exit near the top or ceiling of an elevator car, comprising a removable side panel, folding arms adapted to hold said access means collapsed or extended, a series of foldable steps attached to said side panel, an arm attached to said panel slightly offset from the place of attachment of one of said steps, said arm being likewise attached to said step and provided with a slot adapted to receive a pin attached to a folding arm and slidably in said slot.

14. A means of access to an emergency exit near the top or ceiling of an elevator car, comprising a removable side panel, folding arms adapted to hold said access means collapsed or extended, a series of foldable steps attached to said side panel and a rod governing the folding of said steps, an arm attached to said panel slightly offset from the place of attachment of one of said steps, said arm being likewise attached to

said step and provided with a slot adapted to receive a pin attached to a folding arm and slidably in said slot.

15. In an elevator car, a removable side panel in said car, emergency means of egress near the top or ceiling of said car, and means secured to said removable side panel to permit access to said egress means.

16. In an elevator car, a removable side panel in said car, emergency means of egress near the top or ceiling of said car, and a series of supporting members mounted on the rearward side of said removable side panel for permitting access to said egress means.

17. In an elevator car, emergency means of egress near the top or ceiling of said car, a removable panel in said car, means movable to operative position directly beneath said egress means to permit access thereto, said means being movable to inoperative position concealed behind said removable panel.

18. In an elevator car, emergency means of egress near the top or ceiling of said car, a removable panel in said car, means normally concealed by said panel but adapted on removal of said panel to be moved to position to permit access to said egress means.

19. In an elevator car, emergency means of egress near the top or ceiling of said car, a removable panel in said car, means of access to said egress means, said means being adapted to be concealed from the interior of said car by said removable panel.

20. In an elevator car, emergency means of egress near the top or ceiling of said car, a removable panel in said car, means of access to said egress means, said means being adapted to be concealed from the interior of said car by said removable panel, or to be made available for use within the interior of said car by the removal of said panel.

21. In an elevator car, emergency means of egress near the top or ceiling of said car, an outer wall in said car, a removable panel in said car placed adjacent to said outer wall, and means of access to said egress means mounted between said panel and said wall.

22. In an elevator car, emergency means of egress near the top or ceiling of said car, an outer wall in said car, a removable panel in said car placed adjacent to said outer wall, means of access to said egress means positioned for use upon the removal of said panel from the wall.

23. In an elevator car, emergency means of egress near the top or ceiling of said car, an outer wall in said car, a removable panel in said car placed adjacent to said outer wall, and steps mounted between said wall

and said panel in position to form a means of access to said egress means when said panel is removed.

24. In an elevator car, emergency means of egress near the top or ceiling of said car, an outer wall in said car, a removable panel in said car placed adjacent to said outer

wall, and a series of steps secured to the rearward side of said panel and made accessible through the removal of said panel 10 from its position adjacent said wall.

In testimony whereof, I have signed my name to this specification.

OSCAR A. NORMAN.
